CAMOUFLAGE PENCIL

Charles Scott Althouse, Bern Township, Berks County, Pa.

Application December 9, 1942, Serial No. 468,347

2 Claims. (Cl. 206—56)

My invention relates generally to a cosmetic pencil having a protective manipulating holder casing, and more particularly to a pencil of this nature having two cosmetic pencils normally protectively retained within the casing, with provision for projecting either one beyond the casing for convenient use.

My main object is to provide two color pencils suitable for camouflage use by military forces to render the attacking soldiers less visible in surprise attacks, or wherever camouflage disguise may be found desirable. And for this purpose, the color pencils must be safely retained in a water tight protective casing so as to withstand without harm rough tumbling about in the soldier's pack and soaking in water, and at the same time either pencil must be readily projectable for use and with one hand manipulation if required.

With the above main object in view, and with other objects that will appear later herein, my invention comprises a dual camouflage pencil and protective manipulating holder casing therefor as more fully described hereinafter in connection with the accompanying drawing, and its novel features specifically set forth in the appended claims.

Fig. 1 is a side view indicating a preferred embodiment of my pencil protective casing with closure caps tightly sealing the open ends of the casing.

Fig. 2 shows a longitudinal sectional view of the same.

Fig. 3 is a cross-sectional view, taken on the line 3—3 of Fig. 2.

Fig. 4 is another cross-sectional view taken on the line 4—4 of Fig. 2.

Fig. 5 is a view corresponding to Fig. 2, but showing the end closure caps removed, and one color pencil projected beyond its casing end by pressure exerted on the end of the other color pencil.

Fig. 6 is a sectional view similar to Fig. 2, but indicating modified construction.

The casing 5, is indicated as a tube with screw caps 6, 6 tightly sealing its open ends. It may be formed of metal, plastic, or other suitable material, and the end caps may be hinged, or have a tight telescopic fit, or other like means, the intention being to tightly seal the tube ends by means that may be removed or swung out of the way to uncover said normally closed ends.

In the preferred construction, as clearly seen in Fig. 2, the interior of the tube is of equal diameter throughout its length. A pencil car-

rier is shown as axially positioned within said tube midway of its length, and comprises a spacing rod 10 having camouflage pencil carrying heads 11 and 12, one at each end of said rod, and a mid-length ring eye 13. This carrier is intended to be movable longitudinally along said casing axis in either direction but to be retracted and normally held in midway position within said tube. As shown in Fig. 2, 10 coil springs 14 and 15 each have one end engaging ring eye 13, and their opposite ends are secured to the casing 5, as by riveted end connection to the latter as shown.

The color pencils 20 and 21 are shown as secured to the respective carrier heads 11 and 12 at the opposite ends of the spacing rod 10. These pencils are shown as secured by impaling prongs 22 extending into them from the respective heads 11 and 12, but may be otherwise held. The color pencils 20 and 21 will be of suitable material, and may be of different colors, as required for the specific camouflage needs, and are desirably of a consistency to spread easily and withstand wetting by sweating or rain, but removable by soap and water.

When the pencils 20 and 21 are in their normal retracted position within the casing 5, and the end caps 6, 6, secured to the ends of the casing to make a water-tight sealing, they are 30 fully protected against rough tumbling about in a soldier's kit and will remain dry and ready for use.

When the need arises, the end caps 6, 6, are quickly removable, or swung out of the way, and 35 either pencil may then be projected beyond its casing end by simply pressing a finger, or other pressure means, against the other pencil. In Fig. 5, color pencil 20 is shown projected by end pressure against color pencil 21, a finger 40 for this purpose being indicated in dotted lines. The springs 14 and 15 connecting the ring eye 13 of spacing rod 10 to the casing wall, readily permits this longitudinal movement to project pencil 20, or reversely pencil 21, but on removal of the finger or like pressure, the springs will act to retract the projected pencil by centering the pencil carrier within the length of the casing 5.

In Fig. 6 I have indicated a modified construction, the casing 5' having a hinged end closure cap 6' at one end, and a telescoping cap 6" at the other end tethered by a chain 60. The casing is shown with a midway partition 25, and the spacing rod is shown in the 65 form of a tube 10' having socket heads 11' and

12' to receive and carry the pencils 20' and 21'. And the carrier and its pencils is normally centered by balanced coil springs 26 and 27, which permits longitudinal movement of tube 10' as in the previously described construction to project either pencil by pressure on the other pencil.

Other modifications than those shown in Fig. 6 may be employed, which are within the spirit of my invention as defined in the following claims.

What I claim is:

1. A camouflage pencil comprising a tubular protective and handling casing having oppositely disposed openings adapted to receive closure caps, a spacing bar reversely movable along the longitudinal axis of said casing, tension springs connecting a mid-length portion of said bar to a mid-length portion of the wall of said casing and acting to retract said bar to a mid-length position within the latter, and a

head at each end of said spacing bar for holding a camouflage pencil with both pencils normally held within said casing by said centrally retracted spacing bar, and either one projectable beyond its casing end by end pressure on the other to longitudinally move said spacing bar.

2. A camouflage pencil comprising a protective handling casing having oppositely disposed openings adapted to receive sealing caps, a pencil spacing bar reversely movable longitudinally in said casing, holding means at each end of said bar for a camouflage pencil, and spring means intermediately engaging with said bar and tensioned to normally position said bar centrally within said casing, said bar being longitudinally moved from said tensioned central position by end pressure on one camouflage pencil so as to project the other camouflage pencil outwardly from said casing.

CHARLES SCOTT ALTHOUSE.
